UNITED STATES PATENT OFFICE.

ANDREW WINTERBURN, OF ALBANY, NEW YORK.

IMPROVEMENT IN GRATES FOR FURNACES.

Specification forming part of Letters Patent No. 40,532, dated November 3, 1863.

To all whom it may concern:

Be it known that I, ANDREW WINTERBURN, of Albany, in the county of Albany and State of New York, have invented a new and Improved Fire-Grate for Furnaces, Stoves, &c.; and I do hereby declare that the following is a full, clear, and exact description of the same, reference being had to the accompanying drawings, making a part of this specification, in which—

Figure 1 is a plan or top view of my invention; Fig. 2, a transverse section of the same, taken in the line *x x*, Fig. 1; Fig. 3, a detached view of a plug or pin pertaining to the same; Fig. 4, a side view of one of the projections or journals of the dumping device.

Similar letters of reference indicate corresponding parts in the several figures.

To enable those skilled in the art to fully understand and construct my invention, I will proceed to describe it.

A represents a frame of cast-iron, and of such a form that will fit properly in the bottom of the fire-box designed to receive it. This frame has a rectangular opening within it of sufficient capacity to receive the fire-grate.

B is a cast-iron rectangular frame, corresponding in form to the opening in the frame *A*, and having teeth or projections *a* at the inner surfaces of its sides *b b*, said teeth projecting upward a suitable distance above the sides *b b*, as shown clearly in Fig. 2.

One end of the frame *B* is provided with a tubular projection, *C*, which has a square, *c* on its outer end. This projection *C* is fitted in a bearing, *d*, at one end of the frame *A*. The opposite end of the frame *B* is also provided with a tubular projection, *D*, which is formed of two equal longitudinal parts, *e e'*, one of which, *e*, is cast with the frame *B*, and has a circular end piece, *f*, cast with it, through the center of which there is a hole, *g*. The other part, *e'*, is also provided with a circular end piece, *f'*, cast with it, and of such diameter as to cover the outer end of part *e*. The end piece *f'* also has a hole, *h*, made through its center, through which the end piece *f* of the part *e* a screw, *i*, passes, having a nut, *j*, on its outer end. The tubular projection *D* is fitted in a bearing, *k*, in the end of the frame *A*.

The projections *C D* serve as journals for the frame *B* to admit of the latter being

tilted, in order to dump the fire, which is done by a crank or lever fitted on the square *c* of the projection *C*, and to prevent the frame *B* tilting casually there are lugs *l* cast on one side of the frame *A*, and a button, *m*, is at the opposite side, by turning which, in order to clear the frame *B*, the latter may be tilted, as shown in red in Fig. 2. The projections or journals *C D*, it will be understood, are at the centers of the ends of the frame *B*.

E represents a shaft, the ends of which are fitted in the tubular projections *C D*, and allowed to turn freely therein. The end of this shaft that is fitted in the projection *C* has a square opening made in it to receive a crank, *F*, or a plug, *G*, the latter being shown in Fig. 3, and having a square, *n*, on its outer end. The outer end of the projection *C*, it will be understood, is open, in order to admit of the insertion of the crank or plug.

In inserting the shaft *E* in the projections *C D*, the part *e'* of the latter is detached from the part *e*, and one end inserted in the projection *C*, and the other end laid in *D*, the part *e'* of the latter being then fitted on the part *e*, the nut *j* of the screw *i* being turned, so that the head of the nut may bear against the end of the shaft, and prevent the same from having an unnecessary degree of longitudinal play.

On the shaft *E* there are a series of circular heads, *H*, of equal diameter, and at equal distances apart. These heads may be cast with the shaft *E*, all in one piece, and have such a position as to be in line with the spaces between the teeth *a*, as shown clearly in Fig. 1. This position, however, is not an arbitrary one. The heads *H* are nearly equal in diameter to the width of the space between the teeth *a*, as shown in Fig. 2.

In order to rake or sift the ashes from the fire, the shaft *E* is rotated through the medium of the crank *F*, or a winch placed on the plug *G*, inserted in the end of said shaft. The heads *H*, as they rotate, perform the sifting or raking operation. If desired or necessary, the heads *H* may be of polygonal, elliptical, or other form, in order to shake up the coal. In practice, however, the circular heads seem to operate well.

Having thus described my invention, what

I claim as new, and desire to secure by Letters Patent, is—

1. The manner of fitting the shaft E in the frame B, as shown and described—to wit, by means of the tubular projections C D, the latter, D, being formed of two parts, *e e'*, connected by the screw *j*, all so arranged that the bearings of the shaft E are made to serve as journals for the dumping-frame B.

2. The combination of the shaft E and heads H with the revolving frame B and teeth or projections *a a*, constructed and operating substantially as and for the purposes described.

ANDREW WINTERBURN.
